Patented Dec. 9, 1958

184,039

BATHTUB

Arnold J. Cornelissen, McKeesport, Pa.

Application August 14, 1957, Serial No. 47,366

Term of patent 14 years

(Cl. D4—4)

FIG. 1.

FIG. 2.

FIG. 3.

FIG. 4.

FIG. 5.

Fig. 1 is a top plan view of a bathtub, showing my new design;

Fig. 2 is a front elevational view thereof;

Fig. 3 is a fragmentary and elevational view thereof;

Fig. 4 is an end elevational view thereof, taken from the same end as Fig. 3; and

Fig. 5 is an opposite end elevational view thereof.

I claim:

The ornamental design for a bathtub, substantially as shown.
